ATTORNEY

UNITED STATES PATENT OFFICE

JOHN EDWARD GLOEKLER, OF PITTSBURGH, PENNSYLVANIA

GREENHOUSE TABLE

Application filed December 18, 1930. Serial No. 503,244.

My invention consists of an improvement in tables or tressels for propagation of plant life in greenhouses or the like. The invention comprises a supporting structure 5 provided with a removable flooring and oppositely located sides, upon and between which is deposited a layer of earth for the growing of plants, with the incidents of watering, etc., as is commonly practiced in 10 the art of horticulture.

Ordinarily, such tables are customarily built of wood, which, due to the action of moisture, high temperature, and other conditions of use are subject to rapid decay 15 and deterioration. Such tables have also been manufactured of concrete, with the objectionable items of expense, bulk, and permanency in situ.

In my invention I provide a light, portable construction adapted to be used in a series of connected bench units, in continuous erection and operation, as a trough, and so arranged that the supporting bottom may be quickly changed or renewed from time 25 to time as desired. Further additional advantages are in the manner of construction whereby to provide for rapid elimination and drainage of surplus water, thereby avoiding decay or corrosion, and with the 30 accompanying advantages of lightness, cheapness, portability, and strength, as hereinafter described.

Referring to the drawings showing one preferred form of construction:

35 Fig. 1 is a perspective view showing one of the supporting unit sections erected, broken away at one end and with some of the floor planking in position;

40 Fig. 2 is an end view illustrating the cross sectional construction of such unit;

Fig. 3 is an enlarged sectional detail view on the line III—III of Fig. 1;

Fig. 4 is a similar view on the line IV—IV of Fig. 1;

45 Fig. 5 is an enlarged detail view of one of the corners of the supporting tressel frame, showing the manner of construction;

Fig. 6 is a sectional detail view on the line VI—VI of Fig. 1.

50 While the improved table of this applica-

tion may be used individually, it is preferably employed as a series of bench units, such series being installed in endwise relation to any desired extent, along at one or both sides of the usual passageway in a greenhouse. Such passageway is necessarily comparatively narrow, and it is desirable that as much lateral space as possible may be left below the projecting upper edge of the table or unit. For such purpose the side walls are so mounted as to 55 project materially laterally beyond the lower main supporting tressels.

In the drawings, one entire unitary table or section is generally referred to by the letter A. It is composed of a pair of oppositely 60 located tressels consisting of an upper cross bar member 2 and downwardly extending supporting leg members 3.

These members are preferably of angle shape, formed of a continuous integral bar, 70 with the inner flange cut out at the corner portions as at 4. The bar is bent at right angles at the corners, with the chamfered edges of the inner flange brought together and welded as at 5, Fig. 5. The opposite or 75 horizontal flange of the angle is continuously rounded at the corner, so that it thus forms a strong, continuous, smooth, rounded construction as indicated at 6.

For the purpose of providing rigid outwardly extending supports for the side bars or walls 7 of the table, I utilize brackets 8, consisting of flat bars of metal welded to the upper face of the corner portions of the cross member 2, as at 9. Such bars extend outwardly more or less so as to project materially beyond the leg members 3, and are bent upwardly as at 10, providing the strap extension 11. Inwardly of such extensions 11 are located the side walls 7, usually of wood 80 planking. These are fixedly secured to extensions 11 by screws 12, so that when thus attached at opposite ends to the endmost brackets of the pair of pedestals, the side walls 7 are not only fixedly held in position, 85 but also act as stiffening braces for the entire construction, at opposite sides.

By connecting the walls 7 to the strap 11 by the supporting and connecting screws 12 the lower edge of walls 7 may be spaced up- 90

wardly slightly above the extended arm 8, leaving a clearance opening 13 as in Fig. 6. The purpose of such mounting is, in addition to the rigidity of the construction, to leave 5 an air space 13 between the wood and the metal, so as to avoid the collection and destructive action of moisture on either the wood or metal of the frame.

For the purpose of supporting the loosely 10 mounted floor boards 14, comprising the earth supporting bottom of the table, I utilize a series of metal angle members 15, laid along from one member 2 to the other, as in Fig. 1, and with suitable spacing between them. The 15 angle members 15 are laid with their diverging flanges resting upon the flat upper face of members 2, and thus providing by the middle projecting edge 16, a knife-like supporting and line contact bearing edge for the under 20 side of the planking 14.

Such construction is of especial advantage 25 in reducing to a minimum the contact between the under side of the planking and the supporting angle members 15, so that any 30 water seepage or accumulated moisture will readily run off on one or both of the inclined flange sides and be deposited on the floor of the greenhouse.

Angle members 15 are perforated at their 35 ends and secured through similar perforations in the horizontal flanges of cross bar 2 by means of hook bolts 17, as in Fig. 3. Such hook bolts are tightly connected by nuts 18, and by their construction offer comparatively 40 slight opportunity for accumulation or collection of any destructive moisture.

When thus constructed and assembled in 45 unitary form, the planking 14 may be continuously laid along across the supporting edges of the longitudinal angle members 15. The planks 14 are preferably slightly less in length than the distance between the sides 11, so as to fit easily therebetween, with ample 50 clearance for escape of moisture at each end. Earth 19 may be then deposited upon such flooring, and the table is then capable of use 55 in the customary manner in greenhouse propagation of plant life.

When a series of such unitary sections are 60 arranged longitudinally in position in continuous connected arrangement, they are extremely rigid and assist in bracing each other so that they will easily support any practicable weight and resist various strains of 65 service.

Thus, a skidway may be laid against the 70 endmost cross bar 2 of a series providing for the distribution of earth by wheelbarrows upon such skids and along the flooring 14, either for filling or removal of earth, etc.

In the event of any breakage or ultimate 75 failure of any members of the planking 14, they may be readily substituted by new pieces without the necessity of any fixtures or attachments, as by nailing, bolting, etc., and

the sides 7 may be also replaced in the same manner by mere removal of the screws 12 and substitution of new side pieces.

The projecting brackets 8 contribute largely 80 to the convenience, advantage, and usefulness of the improvement in providing an ample walkway and storage space, inwardly beyond the outermost sides 7.

The construction, manner of operation, advantages and efficiency of the invention will 85 be readily understood and appreciated by all those familiar with the use of plant supporting tables in greenhouse practice or the like. It will be understood that the unit sections may be made in various sizes, dimensions, or 90 otherwise changed in detail construction, or the longitudinal angle members may be suitably spliced and connected, within the scope of the following claims.

What I claim is:

1. A greenhouse table composed of a pair of inverted U-shaped angle iron tressels having outwardly extending L-shaped brackets welded to the opposite corners, side wall planks secured to the inner sides of said brackets, a plurality of inverted angle shape bottom-supporting bars resting on the tressels by their flanges, bolts engaging the flanges by which they are secured to the middle transverse members of the tressels, and bottom planking members laid crosswise thereon between the side wall planks.

2. A greenhouse table comprising in combination a pair of inverted U-shaped supporting tressels made of angle bars having one flange chamfered and welded to form angular opposite corners with the other flange continuously integral, side supporting brackets formed of horizontal bars each welded to the upper corner portion of said integral flange and extending outwardly and upwardly therefrom, side wall planks secured to the inner sides of said upward extensions, a plurality of inverted angle shaped bottom-supporting bars secured to the middle transverse members of the tressels, and bottom planks laid crosswise thereon between the side wall planks.

3. A greenhouse table comprising in combination a pair of inverted U-shaped supporting tressels made of angle bars having one flange chamfered and welded to form angular opposite corners with the other flange continuously integral, side supporting brackets formed of horizontal bars each welded to the upper corner portion of said integral flange and extending outwardly and upwardly therefrom, side wall planks secured to the inner sides of said upward extensions, a plurality of inverted angle shaped bottom-supporting bars resting by their flanges on the tressels and secured thereto and providing upper supporting angular edges, and bottom planks laid crosswise thereon between the side wall planks.

4. A greenhouse table as in claim 2 characterized by the spacing of the side wall planks slightly above the horizontal bracket bars and being secured to the upward extensions thereof by screws.
5. A greenhouse table as in claim 2 characterized by means connecting the angle bars to the integral flange portion of the tressel consisting of hook bolts extending through the flanges of said bars and the tressel and having lower securing nuts.
- 10 6. A continuous greenhouse table composed of a series of longitudinally spaced transverse inverted U-shaped angle iron tressels each having outwardly extending L-shaped brackets welded to the corners of the tressels, side wall planks secured to the inner sides of said brackets, a plurality of inverted angle shape bottom-supporting bars laid continuously along upon their flanges and having hook bolts therethrough secured upon the middle transverse members of the tressels, and bottom planking members laid cross-wise thereon between the side wall planks.
- 15 25 26. In testimony whereof I hereunto affix my signature.

JOHN EDWARD GLOEKLER.
